UNITED STATES PATENT OFFICE.

FRED SUTHERLAND, OF CHICAGO, ILLINOIS.

ATTACHMENT FOR TELEPHONE TRANSMITTERS.

Application filed August 3, 1921. Serial No. 489,437.

To all whom it may concern:

Be it known that I, FRED SUTHERLAND, a citizen of the United States, and a resident of the city of Chicago, county of Cook, and 5 State of Illinois, have invented certain new and useful Improvements in Attachments for Telephone Transmitters, of which the following is a specification.

My invention relates to attachments for 10 telephone transmitters and has for its object the provision of a device which is adapted to close the transmitter of a telephone temporarily while receiving communications thereover in order to prevent 15 sound waves ordinarily set up in noisy offices at the receiving end of the line, entering the transmitter and rendering hearing difficult, while at the same time not interfering with the ordinary use of the instru- 20 ment.

Other objects will appear hereinafter.

The invention consists in the combinations and arrangements of parts hereinafter described and claimed.

25 The invention will be best understood by reference to the accompanying drawings forming a part of this specification, and in which,

Fig. 1 is a front elevation of a telephone 30 showing the device applied to the transmitter thereof,

Fig. 2 is a sectional view on the line 2—2, Fig. 1, showing the invention in its normally inoperative position in full lines, and 35 in operative position in dotted lines,

Fig. 3 is a sectional view on the line 3—3, Fig. 2, and

Fig. 4 is a sectional view on the line 4—4, Fig. 2.

40 It is well known that it is ordinarily very difficult to hear well over a telephone in a location where there is a great deal of noise, due to the fact that sound waves thus set up pass into the transmitter of the telephone and are communicated to the receiver through the telephone casing or otherwise. It is also well known that if the transmitter is closed with the hand, the voice speaking becomes much more clear and dis- 45 tinct. It is, however, often inconvenient to use the hand for closing the transmitter, it being frequently necessary to have the use of one hand for writing down messages, etc., the other hand, of course, being occupied in 50 holding the receiver to the ear. My invention provides a device which is adapted to

be attached to a telephone transmitter in such a manner that it will not interfere with the ordinary use of the instrument, but which can be operated by slight pressure of 60 the chin or cheek thereon to close the transmitter while receiving a message to prevent extraneous sounds confusing and rendering indistinct the speech of the person at the other end of the line.

65 My invention broadly consists of a closure member mounted in the transmitter of a telephone and normally held in inoperative position in order not to interfere with the ordinary use of the instrument. When it 70 is desired to close the transmitter to exclude extraneous sounds therefrom, slight pressure with the chin or cheek of the user will move the closure member to operative position and effectively close said transmitter.

75 In carrying out my invention I preferably employ a base plate 1 of such size and shape as to fit within a telephone transmitter. Such plate 1 preferably has apertures therein corresponding to the apertures ordinarily 80 provided in transmitters, and is fastened in position by means of small bolts 2 passing through the apertures and secured by means of nuts 3. In this connection it may be re- 85 marked that obstruction of some of the apertures ordinarily provided in telephone transmitters in no way detracts from the efficiency of the instrument in transmission of speech, since it is known that a smaller number of apertures than ordinarily pro- 90 vided will produce satisfactory results.

95 Mounted on the plate 1 is a post 4 which extends to a point outside of the transmitter and has a reduced portion 5 at its end which is preferably exteriorly threaded. Slidably mounted on the post 4 is a sleeve 6 which carries on its inner end a plug 7 of any desirable material, preferably of rubber. The plug 7 may be of any suitable shape, but I prefer to use a plug of the type shown, 100 which may be concaved or recessed as at 8, such recess, when the device is in inoperative position, cushioning the sound waves deflected by the base plate 1, and preventing setting up of clashing waves and consequent 105 buzzing and other objectionable noises.

110 Seated on the shoulders of the post 4 formed by the reduced portion 5 is a washer 9, of rubber, or any desirable material, which forms a stop for limiting the outward movement of the sleeve 6. A nut 10 threaded on the reduced portion 5 holds the washer

9 in position. An expansible spring 11 is mounted on the reduced portion 5 and has one end abutting against the washer 9, the other end of such spring engaging the inner surfaces of a cap 12 which is threaded onto the outer end of the sleeve 6 as shown in Fig. 2. The spring 11 thus normally holds the sleeve 6 and plug 7 away from the plate 1 and the sides of the transmitter, and consequently permits free passage of sound waves into the transmitter. When it is desired to close the transmitter in order to exclude sound therefrom, a slight pressure exerted on the cap 12 will force the plug 7 between the converging walls of the transmitter and thus effectually close same. When released the plug will resume its normal inoperative position due to the pressure exerted by the spring 11 on the cap 12 and the sleeve 6.

Thus it will be seen that when using a telephone in a noisy office, or in any situation where there is a great deal of noise, the transmitter can be closed by a slight pressure on the device with the cheek or chin of the user, in order to improve the clearness and distinctness of the voice in the receiver, and at the same time to leave one hand free for writing, which is important in business offices.

The device can be manufactured cheaply and economically, is very simple in construction and operation, and has great practical importance.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claims.

Having described my invention, what I claim as new and desire to secure by Letters Patent, is:—

1. The combination of a telephone transmitter, and an elastic member smaller than the interior of said transmitter adapted to be thrust against the bottom of said transmitter to spread same so as to fill the space between the walls thereof; and guide means in said transmitter slidably carrying said elastic member, substantially as described.

2. The combination of a telephone transmitter, and an elastic member smaller than the interior of said transmitter having a concaved abutting face adapted to be thrust against the bottom of said transmitter to spread same so as to fill the space between the walls of said transmitter; and guide means in said transmitter slidably carrying said elastic member, substantially as described.

3. In combination with a telephone transmitter, a closure arranged to be thrust into the mouth of said transmitter to exclude sound therefrom; a guide mounted in said transmitter; and means for slidably mounting said closure on said guide, substantially as described. 70

4. In combination with a telephone transmitter, a closure arranged to be thrust into the mouth of said transmitter; a guide mounted in said transmitter; means for slidably mounting said plug on said guide whereby same may be used to block said transmitter to exclude sound therefrom; and means for normally holding said plug in 80 inoperative position, substantially as described. 75

5. In combination with a telephone transmitter, a guide member secured thereon; a sleeve slidably mounted on said guide member; a closure member mounted on said sleeve; and resilient means for normally retaining said sleeve in inoperative position, 85 substantially as described. 85

6. In combination with a telephone transmitter, a guide; a sleeve having one end closed slidably mounted on said guide; a stop on said guide; and resilient means disposed between said guide and the closed end of said sleeve for normally retaining 95 said sleeve in retracted position, substantially as described. 90

7. In combination with a telephone transmitter a supporting member; a sleeve mounted on said supporting member and 100 having a plug secured to the end thereof; a chamber in said plug; and means for holding said plug in inoperative position, substantially as described. 105

8. In combination with a telephone transmitter a supporting member; a sleeve slidably mounted on said supporting member; a cap engaging the outer end of said sleeve; means on the opposite end of said sleeve for closing said transmitter; and resilient means mounted between said cap and said supporting member for normally retaining 110 said closing means in inoperative position, substantially as described. 110

9. In combination with a telephone transmitter a supporting member; a sleeve slidably mounted on said supporting member; means on said sleeve for closing said transmitter; a stop on said supporting means for limiting the sliding movement of the sleeve 115 thereon; a cap engaging said sleeve and movable therewith; and resilient means mounted on said supporting member and engaging said cap to normally retain said closing means in inoperative position, substantially as described. 120

10. In combination with a telephone transmitter a supporting member; a sleeve slidably mounted on said supporting member and having means for closing the trans- 125 130

mitter; a reduced portion on said supporting member; a stop mounted on said reduced portion; a nut mounted on said reduced portion to hold said stop in position; 5 and resilient means for retaining said sleeve against said stop, substantially as described.

11. In combination with a telephone transmitter a base plate; apertures in said base plate coinciding with the apertures in 10 the transmitter; bolts passing through said apertures to fasten said base plate in position; a post mounted on said base plate; means mounted on said post for closing said transmitter; and means for normally 15 retaining said closing means in inoperative position, substantially as described.

12. In combination with a telephone transmitter a base plate adapted to fit in the transmitter; a post mounted on said 20 plate and projecting to a point outside of

said transmitter; a sleeve slidably mounted on said post; a plug mounted on the inner end of said sleeve; a reduced portion on said post having exterior threads thereon; a washer mounted on said reduced portion 25 to serve as a stop for said sleeve; a nut on said reduced portion to retain said washer in position; an expansible spring mounted on said reduced portion; and a cap mounted on said sleeve and engaging said spring to 30 retain said plug in inoperative position, substantially as described.

In testimony whereof I have signed my name to this specification in the presence of two subscribing witnesses.

FRED SUTHERLAND.
